LADY'S ONE PIECE GARMENT

Darlene M. Bartholomew, 5731 Karen Ave.,
Cypress, Calif.

Filed Jan. 4, 1963, Ser. No. 73,049

Term of patent 14 years

(Cl. D3—17)

FIG. 1

FIG. 1 is a front view of a lady's one piece garment showing my new design;

FIG. 2 is a side view thereof; and

FIG. 3 is a back view.

I claim:

The ornamental design for a lady's one piece garment, as shown.
